UNITED STATES PATENT OFFICE.

WILLARD B. MCBURNEY, HORATIO T. BARKSDALE, AND JOHN B. HOWE, OF ATLANTA,
GEORGIA.

REFRIGERATING APPARATUS.

1,133,163.

Specification of Letters Patent. Patented Mar. 23, 1915.

Application filed September 2, 1913. Serial No. 787,765.

To all whom it may concern:

Be it known that we, WILLARD B. MCBURNEY, HORATIO T. BARKSDALE, and JOHN B. HOWE, citizens of the United States, residing at Atlanta, in the county of Fulton and State of Georgia, have invented certain new and useful Improvements in Refrigerating Apparatus; and we do hereby declare the following to be a full, clear, and exact description of the invention, such as will enable others skilled in the art to which it appertains to make and use the same.

Our invention relates to refrigerating apparatus of the absorption type, and it consists in the constructions, combinations and arrangements herein described and claimed.

An object of our invention is to provide an improved apparatus for simplifying the operation and economizing the steam consumption in absorption refrigerating apparatus employing high pressure generators and low pressure pumps.

A further object of our invention is to provide an improved apparatus adapted to be readily applied to existing absorption refrigerating plants.

In existing installation of absorption refrigerating plants employing high pressure generators and low pressure steam pumps, live steam is supplied from a boiler directly to the coil of the generator; a boiler pressure of approximately 100 lbs. being employed for maintaining steam at sufficient pressure and temperature in the generator coil to drive off the ammonia gas under a high pressure, often approximating 180 lbs. and over. The steam is discharged from the high pressure generator coil through suitable separators to the reboiler where it is condensed and then distilled to produce pure water for filling the ice cans. The low pressure steam pumps of such plants are also supplied directly from the high pressure boiler thus required for this type of generator, in order to economize space and the costs of installation and operation. This reduced pressure supply to the pumps is effected by the engineer closing the main valves in the steam pipes of the several pumps to a greater or less degree for throttling the high pressure boiler steam down to the required pump pressure of approxi-

mately 40 lbs. This results in an inefficient and inconvenient operation, in which a large amount of heat is wasted in the steam discharge from the high pressure generator, and in which the steam valves of the generator and several pumps have to be independently adjusted to vary the rate of operation of the refrigerating apparatus. 55

In our improved apparatus, steam is supplied directly from the boiler to the generator coil at high pressure for driving off the ammonia gas under the high pressure in the generator, and the discharge from the generator coil is conducted to the several low pressure steam pumps at a pressure of approximately 40 lbs.; the exhaust from the several pumps being directly through a condenser which is cooled by the passage 60 through it of the cool, strong ammonia liquor coming from the absorber. The liquor in the absorber is maintained at as low a temperature as possible, in order that it will absorb a large amount of ammonia 65 gas. This same liquor, however, is, after it has passed into the generator coil, heated to a high temperature, in order to drive off a large amount of ammonia gas. It is evident, therefore, that this strong liquor must 70 be subjected to considerable preliminary heating, before the ammonia gas is given off. Now this heating may all be done in the generator coil, or it may be done in part by preliminarily heating the liquor on its 75 way to the generator coil. It is further evident that the greater the extent of this preliminary heating, outside the generator coil, the less the extent of the heating within the generator coil, and the greater the economy 80 of steam in the generator coil. In addition to this demand for preheating the ammonia liquor, there is also the demand for cooling means for a condenser, or condensers for the exhaust from the ammonia pumps. 85 Now this invention introduces means whereby the fulfilment of the one demand fulfils the other, that is, the cooling of the exhaust steam is effected by the cool liquor, and the preheating of the cool liquor is correspondingly effected by the exhaust steam. A double economy is here apparent:—a saving in 90 water for condensing means for the exhaust from the several pumps, and a saving in 95 water for condensing means for the exhaust from the several pumps, and a saving in 100

the amount of subsequent heating, in the generator coil, of the strong liquor. This result is attained by what is simply a heat exchanger, which is at once a condenser and a heater. The steam to be condensed and cooled is passed through this condenser-heater in one direction, and the liquor to be heated is passed through in the other direction, the steam and liquor, of course, traveling in separate channels, and the flow of heat taking place through the separating wall. This heat-exchanging means, while analogous to the well-known exchanger, in which the cool liquor from the absorber cools the hot, weak liquor from the generator, and at the same time is heated in so doing, differentiates therefrom in that in our arrangement this cool liquor cools the condensing means in the condenser for the exhaust of the circulating pumps, and at the same time is heated in so doing. Our arrangement is intended to be used in conjunction with an exchanger, of the usual type, and so placed that the cool liquor from the absorber passes first through the condenser-heater and then through the exchanger.

This provides a highly advantageous construction, in which the steam discharged at considerable pressure, approximately 40 lbs. and over, from the coil of the high pressure generator is used for driving the low pressure steam pumps and the final exhaust from said pumps is delivered to the reboiler, after having passed through the combined condenser and heater. Further, very little adjustment of the steam supply valves of the several pumps is necessary when varying the rate of operation of the refrigerating apparatus, since all adjustments of the steam supplied to the high pressure generator act automatically to correspondingly vary the quantity of actuating steam supplied to the pumps. Our invention therefore provides an efficient and inexpensive construction adapted to be readily applied to existing absorption refrigerating plants, and which is free from the inconvenience and irregularity of action caused in present installations by the uncertain setting of the independent steam supply valves of the several low pressure pumps to accommodate the variations of service conditions.

The accompanying drawing, forming a part of this application, illustrates diagrammatically one embodiment of our invention, in which—

1 indicates a steam boiler connected by a pipe 2 directly to the coil 3^b of a high pressure generator 3; said pipe being shown provided with a manually-operated main valve 4 and a safety valve 5. In the usual type of high pressure generators, a boiler pressure of approximately 100 lbs. is employed 65 for furnishing steam to the generator coil

at sufficient pressure to maintain the required temperature for driving off the ammonia gas under the high generator pressure, often approximating 180 lbs. 3^a is a suitable outlet for the ammonia gas set free 7 in the generator, that is led into the condensing and refrigerating apparatus.

The steam is discharged from the high pressure generator 3 through a pipe 6 to a receiver 7, where oil and water of condensation are separated and removed by a drain 8 provided with a valve 9. The receiver is connected to the low pressure steam pump 10 for the cooling water by a steam pipe 11 provided with a steam supply valve 12, and the steam exhaust from said pump is conducted by a pipe 13 provided with a valve 22 to a condenser and heater 14. The cooling medium for this condenser is the cool, rich ammonia liquor coming from the absorber 31. 8^a This cool liquor coming from the absorber 31 enters the pipe 14^a, passes thence through the coils in the condenser and heater, wherein it cools and condenses the steam, and itself becomes heated, and passes out through the pipe 14^b through an exchanger (not shown) of the usual type and thence to the generator. A pipe 15 leads from the receiver 7 for supplying steam to the low pressure ammonia pump 16 and brine pump 17; the steam supplied to said pumps being controlled by manually-operated valves 18 and 19, respectively. The steam from the low pressure pumps 16 and 17 exhausts through the pipes 23 and 24, respectively, to the common exhaust pipe 13 leading to the condenser and heater 14; said exhaust pipes 23 and 24 being controlled by valves 25 and 26. The steam after thus passing successively through the high pressure generator and low pressure pumps is exhausted into the condenser and heater 14 and finally discharged therefrom through a pipe 27 to the reboiler 28. A pipe 29, controlled by a valve 30, connects the receiver 7 and reboiler 28 to provide means for admitting steam directly from said receiver to the reboiler; thereby enabling the apparatus to be readily adjusted for uniform operation under service conditions in which the generator uses more steam than is required by the several pumps. A high pressure steam line may, however, be used to supply the several pumps, if they are of the high pressure type, in which case the receiver or throttling valves would not be necessary.

As shown, the pipe 29 preferably leads from the bottom of the receiver 7, so that all water of condensation will be forced into the reboiler by the steam pressure in said receiver when the valve 30 is open. From the above description it will be understood that our invention provides a simple and inexpensive construction adapted to be readily applied to existing absorption re- 120

frigerating plants having high pressure generators and low pressure steam pumps, for insuring economy in steam consumption and a regular operation under all service 5 conditions.

We have illustrated and described preferred and satisfactory constructions, but changes could be made within the spirit and scope of our invention.

10 We claim:—

1. In an absorption refrigerating apparatus, the combination of an ammonia generator, a coil within said generator, a plurality of low pressure steam circulating 15 pumps, a source of high pressure steam connected directly to the generator coil, and independent valve-controlled connections for supplying steam from said high pressure generator coil to said several low pressure 20 sure pumps.

2. In an absorption refrigerating apparatus, the combination of an ammonia generator, a coil within said generator, a plurality of low pressure steam circulating 25 pumps, a source of high pressure steam connected directly to the generator coil, independent valve-controlled connections for supplying steam from said high pressure generator coil to said several low pressure 30 pumps, a reboiler, and means for conducting the exhaust steam from said several pumps to said reboiler.

3. In an absorption refrigerating apparatus, the combination of an ammonia generator, a coil within said generator, a plurality of low pressure steam circulating 35 pumps, a source of high pressure steam connected directly to the generator coil, a receiver for the steam discharged from said high pressure generator coil, independent valve-controlled connections for supplying steam from said receiver to said several low pressure pumps, a reboiler, means for conducting the exhaust steam from said several 40 pumps to said reboiler, and a valve-controlled by-pass from said receiver to said reboiler.

4. In an absorption refrigerating apparatus, the combination with an ammonia 50 generator, of a coil within said generator, a supply of steam for said generator coil, a plurality of circulating pumps, independent valve-controlled connections between said generator coil and said pumps, a condenser, 55 means for leading the exhaust steam from said pumps into said condenser, an absorber,

and means for leading the liquor from the absorber through said condenser.

5. In an absorption refrigerating apparatus, the combination with an ammonia generator, of a coil within said generator, a supply of high pressure steam for said generator coil, a plurality of low pressure circulating pumps, a receiver, means for leading the exhaust steam from said generator coil into said receiver, independent valve-controlled connections to supply steam to said pumps from said receiver, a condenser, means for leading the exhaust steam from said pumps into said condenser, an absorber, and means for leading the liquor from the absorber through said condenser. 65

6. In an absorption refrigerating apparatus, the combination with an ammonia generator, of a coil within said generator, a supply of steam for said generator coil, a plurality of circulating pumps, independent valve-controlled connections between said generator coil and said pumps, a condenser, means for leading the exhaust steam from 70 said pumps into said condenser, an absorber, means for leading the liquor from the absorber through said condenser, a reboiler, and means for leading the condensed steam from said condenser to said reboiler. 75

7. In an absorption refrigerating apparatus, the combination with an ammonia generator, of a coil within said generator, a supply of high pressure steam for said generator coil, a plurality of low pressure circulating pumps, a receiver, means for leading the exhaust steam from said generator coil into said receiver, independent valve-controlled connections to supply steam to said pumps from said receiver, a condenser, 90 means for leading the exhaust steam from said pumps into said condenser, an absorber, means for leading the liquor from the absorber through said condenser, a reboiler, means for leading the condensed steam from 95 said condenser to said reboiler, and a valve-controlled by-pass from said receiver to said reboiler. 100
